UNITED STATES PATENT OFFICE.

HERBERT J. CRABBS, OF PITTSBURGH, PENNSYLVANIA, ASSIGNOR TO WESTINGHOUSE ELECTRIC & MANUFACTURING COMPANY, A CORPORATION OF PENNSYLVANIA.

REAR-OF-PANEL KNIFE-BLADE SWITCH.

Application filed January 20, 1922. Serial No. 530,710.

My invention relates to knife switches, and thereof. The member 16 consists of a metal rod having reduced end portions 17 more especially to the rear-of-panel-mounted pivotally supported in the forked end of the lever 15 and provided with cotter-pin type of switch in which the contact elements openings 18 and a central opening 19 for are remote from the operating side or active engaging a stud member 20 which is secured to front. 5 the yoke 14 by a screw-thread-and-unit combination 21.

It is among the objects of this invention to provide a switch of the above designated type which shall be simple to operate, which shall consist of a minimum number of parts, 10 which shall be economical to manufacture and which shall be mechanically efficient.

In my co-pending application Serial No. 503,859, filed September 28, 1921, for knife-blade switches, is described a rear-of-panel-mounted knife switch of a unitary structure 15 which may be secured as a unit to a switchboard panel. In my present invention I provide an improvement in the mounting of the lever and in the sliding engagement of the 20 lever with the switch-blade element which engages the contact members.

In the accompanying drawings constituting a part hereof, in which like reference characters designate like parts,

Figure 1 is a rear elevational view of a 25 knife switch embodying my invention;

Fig. 2 is a side elevational view thereof, 30 partially in section;

Fig. 3 is a plan view of a pivoting slide 35 member for joining the lever with the contact elements;

Fig. 4 is a rear elevational view of a modification of the switch; and

Fig. 5 is a side elevational view thereof, 40 partially in section.

As shown in Figs. 1 to 3, I provide a switch base 1 of suitable material, such as marble, slate or an insulating composition, which is secured to a mounting bracket 2 and mounted 45 on a switchboard panel 3 by suitable screw bolts 4 which also support a metal plate 5 which functions as a lever stop. A plurality of contact members 6 and hinge jaws 7 are mounted on the base 1, and the hinge jaws 45 and contacts are provided with lead terminals 8 and 9, respectively.

A plurality of knife-blade members 10 are pivotally mounted on the hinge jaws 7 and are provided with a plurality of auxiliary 50 quick-break snap-switch members 11 and 12, cross-connected by a coil spring 13. The knife-switch members 10 are connected together by an insulating yoke 14 which is movably connected to an operating lever 15 by a 55 pivoting member 16 mounted in the forked

end thereof. The member 16 consists of a metal rod having reduced end portions 17 pivotally supported in the forked end of the lever 15 and provided with cotter-pin openings 18 and a central opening 19 for engaging a stud member 20 which is secured to the yoke 14 by a screw-thread-and-unit combination 21. 60

The operating lever 15 is pivotally mounted on a supporting bracket 22 and is provided with a yieldable contact lug 23 which is secured by coil springs 24 to provide a yielding support in the notched contact surface 25 of the bracket 22. The lever 15 is further provided with an insulating handle 26. 70

As shown in Figs. 4 and 5, the pivot-sliding joint connection between the operating lever and the movable contact or knife-blade members is provided by suspending the member 16 from the insulating yoke 14 on a supporting bracket 27 secured to the yoke and by securing the stud member 20 on the end of the lever 15. This is just the reverse construction of the switch shown in Figs. 1 to 3 and functions in a similar manner. The lever-supporting bracket 22 is provided with an angular plane faced contact surface 28 for engaging a yieldingly mounted pressure plate 29 and secured to the lever and supported by a spring 30 to maintain the lever 15 in either 80 the closed or the open position. 75

The switch mechanism operates as follows: The operating lever 15 is placed in a position perpendicular to the panel 3 holding the knife-blade members 10 in alignment there- 90 with and disconnected from the contacts or switch jaws 6. The lever 15 is moved up or down into the positions shown in Fig. 2, the sliding-joint connection between the knife-blade members and the lever arm permitting 95 a rotative movement of the member 16 and a simultaneous sliding of the stud member 20 in the opening 19 thereof. This motion provides an anti-frictional contact between the members to permit bringing the switch blades 100 into contact with the jaws 6.

When the switch is again opened, the auxiliary spring-actuated-break-switch member 11 maintains contact with the switch jaws 6 until the main knife-blade member 10 has 105 swung clear and broken contact therewith. The tension of spring 13 is so adjusted that the blade member 11 will break contact at this point with such speed as to avoid fusion or burning caused by arcing produced by a 110

slow breaking of the engagement of the knife-blade members and the corresponding stationary contact members.

From the above description of my invention, it will be readily understood that a double throw back-of-board switch made in accordance therewith provides a simple and efficient switch mechanism which is inexpensive to manufacture and simple and positive in its operation.

Although I have described a specific embodiment of my invention, it will be obvious to those skilled in the art that various modifications may be made in the details of construction thereof without departing from the principles herein set forth. For instance, the general details, such as switch jaws, pivot supports, knife-blade terminal screws and the like, may be of any suitable shape and design, the mounting brackets or switch base may be designed to suit any specific application and the auxiliary switch jaws or the

yielding support of the levers may be omitted. These and various other changes in details of construction may be made in my structure without departing from the spirit and scope of my invention.

I claim as my invention:

The combination with a switch panel, of a base adapted to be secured thereto, a plurality of contact members mounted on said base, some of said contact members being pivotally mounted and connected by an insulating yoke, a bracket for pivotally mounting an operating lever, and a member pivotally mounted on the end thereof, said member having an opening for slidingly engaging a stud projecting from said insulating yoke.

In testimony whereof, I have hereunto subscribed my name this 10th day of January, 1922.

HERBERT J. CRABBS.
